UNITED STATES PATENT OFFICE.

ENOCH E. NEAL, OF MALDEN, MASSACHUSETTS.

COAL CHUTE.

1,423,872.

Specification of Letters Patent. Patented July 25, 1922.

Application filed March 23, 1921. Serial No. 454,825.

To all whom it may concern:

Be it known that I, ENOCH E. NEAL, a citizen of the United States, residing at Malden, in the county of Middlesex and 5 State of Massachusetts, have invented new and useful Improvements in Coal Chutes, of which the following is a specification.

This invention relates to improvements in coal chutes and the like.

10 The object of the invention is to so construct the sections comprising a telescoping coal chute that in the event of more than one section being required, two or more may be easily and quickly secured together to form a chute of the length required.

Another object of the invention is to provide a novel mechanism for securing the sections of the coal chute together, said mechanism when not in use being automatically withdrawn within a tubular casing located beneath one end of said sections where it is concealed from view and safe from damage resulting from hard usage.

25 The invention consists in the combination and arrangement of parts set forth in the following specification and particularly pointed out in the claims thereof.

Referring to the drawings:

30 Figure 1 represents a plan view of a portion of two sections constituting a telescoping coal chute, said sections being secured together in accordance with my invention.

Fig. 2 is a transverse section partly in elevation taken on the line 2—2 of Fig. 1 35 and looking toward the right in said figure.

Fig. 3 is a detail, sectional elevation illustrating a portion of the mechanism by means of which the sections of the coal chute are secured together.

40 Fig. 4 is an end elevation of the mechanism illustrated in Fig. 3 as viewed from the right of said figure.

Fig. 5 is a detail, vertical section taken on the line 5—5 of Fig. 2.

45 Fig. 6 is an end elevation similar to Fig. 4 illustrating a modified embodiment of my invention.

Fig. 7 is a detail section taken on the line 7—7 of Fig. 6.

50 Like numerals refer to like parts throughout the several views of the drawings.

In the drawings, A and B represent a pair of interchangeable sections comprising a 55 telescoping coal chute C, said sections being identical in construction and adapted to fit closely one within the other when completely

telescoped. The sections A and B each comprise a runway constructed of sheet metal having a bottom 6 and sides 7 preferably perpendicular to said bottom. The bottom 6 is widest at the end a and gradually decreases in width toward the opposite end b, while the sides 7 are highest at the end a and also gradually decrease in height from said end toward the end b. The sides 7 of each section are reinforced by angle irons 8 which extend the length of each section, a downwardly projecting flange 9 being riveted to the outer surface of each side 7 adjacent to the upper edge thereof, and another flange 10 projects inwardly from said side.

The opposite ends of each section A and B are strengthened by reinforcing members 11 and 12, the member 11 being secured at the end a while the member 12 is secured at the end b. The member 11 extends across the under side of the bottom 6 and has upwardly projecting arms 13 to which the sides 7 are secured. The upper ends of the arms 13 project inwardly at 14 and are secured to the inwardly projecting flanges 10 of the angle irons 8 and at one side of each section the projections 14 are extended a short distance beyond the inner edge of the inwardly projecting flange 10 and are then bent downwardly at 15 to form a stop for the purpose of holding one of the angle irons 8 of one section beneath the corresponding angle iron 8 of the other section when said sections are secured together as illustrated in Figs. 1 and 2.

As the sections A and B are moved one upon the other to vary the overall length of the chute C the sides 7 upon the upper side of Fig. 1 or at the left hand side of Fig. 2 are always held in the same relative position to each other. The distance between the sides 7 at the bottom of Fig. 1 or at the right hand side of Fig. 2, however, varies as the section B is moved within the section A. The mechanism for securing the last mentioned sides together is as follows:—Secured upon the underside of the reinforcing member 11 in any desired manner, but preferably by being welded thereto, is a tube 16 which extends approximately the width of the section at the wide end thereof. One end of the tube 16 is closed by a suitable plug 17, while a sleeve 18 is secured within the tube 16 adjacent to its other end. A flexible member, preferably 100 a chain 19, is normally located within the

105

110

tube 16 and is approximately the length of said tube. To the inner end of the chain 19 a circular plate 20 constituting a spring seat is attached in any suitable manner, 5 while a hook 21 is attached to the outer extremity of said chain.

Surrounding the chain 19 within the tube 16 is a spring 22, one end of which rests 10 against the spring seat 20 and the other end against the inner end of the sleeve 18. The extent to which the chain 19 may be withdrawn from within the tube 16 is limited by a link 23 constituting a stop which is of sufficient size to be prevented from passing 15 through an opening 24 provided at the inner end of the sleeve 18. Another link 25 which is the outer link of the chain 19 and which is of similar size to the link 23 limits the extent to which the hook 21 may 20 be drawn into the tube 16 by the spring 22, the position of said hook at this time being such that the outer end thereof may be engaged by the finger tips and pulled outwardly. A slot 26 is provided at the right 25 hand end of the tube 16, Fig. 2, and also extends through one side of the sleeve 18 and said slot is adapted to receive the various links comprising the chain 19 when 30 said chain is withdrawn from the tube 16 as illustrated in said Fig. 2, and when said chain is in said position it is prevented from being again drawn into the tube 16 by the spring 22 or from being pulled still further outwardly from said tube. The hook 35 21 is adapted to be secured to the flange 10 as illustrated in Fig. 2. The material comprising the bottom 6 of each section may be bent downwardly at the wide end of said section and extended in front of and beneath the tube 16 at 27 where it may be secured in any desired manner.

The general operation of my improved coal chute is as follows:—When it is found that one of the sections A or B is not long 45 enough to deliver the coal to the point desired, two or more of the sections are placed together as illustrated in Figs. 1 and 2. The chute C is then placed in an inclined position and the highest end thereof supported in any desirable manner. In this position the end 7 of the section B will contact with the bottom 6 of the section A, and at one side the angle iron 8 of the section B is located beneath the angle iron 8 50 of the section A with the upper surface of the lower angle iron contacting with the undercorner of the upper angle iron at the left hand extremity of the section A, Fig. 1. In this position the projection 15 will 55 prevent the sides 7 at the left hand side of Fig. 2 from moving further apart.

The chain 19 which has up to this time been located entirely within the tube 16 is 60 now pulled outwardly therefrom by pinching the hook 21 between the fingers and

pulling outwardly thereon. The chain 19 is pulled outwardly a sufficient distance for the hook 21 to be attached to the flange 10 as illustrated in Fig. 2 and in this position the link of the chain 19 which aligns 70 with the slot 26 at the end of the tube 16 is inserted within said slot. As long as the chain remains within the slot 26, said chain cannot be pulled any further outwardly, nor can the spring 22 within the 75 tube 16 pull said chain inwardly. The sides 7 of the sections A and B at the right hand side of Fig. 2 are then securely fastened together. When the hook 21 is removed from the flange 10 and the chain 19 is removed 80 from the slot 26 the spring 22 will automatically draw said chain into the tube 16 and again assume a position as illustrated in Fig. 3. The device as illustrated and described is extremely simple and easy to operate and when the sections comprising the chute are not secured together and the chain is located in the position illustrated in Fig. 3 it is entirely concealed and cannot be damaged by any hard usage that it may receive. 85

In Figures 6 and 7 I have illustrated a modified embodiment of my invention in which the tube 16 has a plate 28 securely fastened therein in any suitable manner and 90 said plate constitutes a partition which extends transversely of said tube within the interior thereof a short distance from the open end. The plate 28 is provided with a slot 29 formed therein which is adapted 95 to receive the links of the chain 19 in a manner similar to the slot 26 previously described. A sleeve 30 is located within the tube 16 a short distance from the open end thereof and said sleeve is provided for the 100 purpose of limiting the extent to which the chain 19 may be withdrawn from the tube or drawn into said tube.

While the sections of the coal chute illustrated and described herein are strengthened by angle irons extending along their upper edges, said angle irons being utilized in securing the sections together, it is evident that the sections may be provided with other types of flanges which may co-operate 110 equally well in securing the sections together and also in reinforcing said sections as, for example, by providing the well known rolled edge. Furthermore while I have illustrated and described this invention in 115 connection with a coal chute, it is evident that the mechanism could be utilized in connection with other devices all of which may fall with the scope of the appended claims.

I claim:

1. A device of the character described having, in combination, a plurality of chute sections, a tube fast to the underside of one of said sections and provided with a slot at one end thereof, a flexible member nor- 120

upon the other, each of said sections embodying therein angle irons extending longitudinally thereof upon each side thereof, means to hold an angle iron at one side of one 5 of said sections beneath the corresponding angle iron of the other of said sections and thereby fasten said sections together at one side thereof and flexible means secured to one end of the lower of said sections and 10 adapted to be attached to the upper of said sections and thereby fasten said sections together upon the other side thereof.

9. A chute embodying therein a plurality of interchangeable sections slidable one 15 upon the other, each of said sections embodying therein angle irons extending longitudinally thereof upon each side thereof, means to hold an angle iron at one side of one of said sections beneath the corresponding 20 angle iron of the other of said sections and thereby fasten said sections together at one side thereof, a tube fast to the end of said sections and provided with a slot at one end thereof, a flexible member normally located in said tube adapted to be pulled therefrom, inserted within said slot and attached to the upper of said sections and means to pull said flexible member into said tube when said member is released from said 25 last-mentioned section and removed from said slot.

10. A chute embodying therein a plurality of interchangeable sections slidable one upon the other, each of said sections embodying 30 therein angle irons extending longitudinally thereof upon each side thereof, a reinforcing member fast to one end of each of said sections and having an arm formed integral therewith adapted to hold an angle 35 iron located at one side of one of said sections beneath the corresponding angle iron of the other of said sections and thereby fasten said sections together at one side thereof, a tube fast to the underside of said reinforcing member and provided with a slot at one end thereof, a flexible member normally located in said tube adapted to be pulled therefrom, inserted within said slot and attached to the upper of said sections and means to pull said flexible member into said tube when said member is released from said 40 last-mentioned section and removed from said slot.

11. A chute embodying therein a plurality 45 of interchangeable sections slidable one upon

the other, each of said sections embodying therein angle irons extending longitudinally thereof upon each side thereof, a reinforcing member fast to one end of each of said sections and having an arm formed integral therewith adapted to hold an angle 60 iron located at one side of one of said sections beneath the corresponding angle iron of the other of said sections and thereby fasten said sections together at one side 65 thereof, a tube fast to the underside of said reinforcing member and provided with a slot at one end thereof, a chain normally located within said tube, a portion thereof being adapted to be removed therefrom and one of the links thereof inserted within said slot and secured thereby, means to attach said chain to the upper of said sections and means to pull said chain into said tube when said chain is released from said last-mentioned section and removed from said slot.

12. A chute embodying therein a plurality of interchangeable sections slidable one upon the other, each of said sections embodying therein angle irons extending longitudinally 70 thereof upon each side thereof, a reinforcing member fast to one end of each of said sections and having an arm formed integral therewith adapted to hold an angle iron located at one side of one of said sections beneath the corresponding angle iron of the other of said sections and thereby fasten said sections together at one side thereof, a tube fast to the underside of said reinforcing member and provided with a slot at one end 75 thereof, a sleeve located within said tube at one end thereof, a chain normally located within said tube, a portion thereof being adapted to be removed therefrom and one of the links thereof inserted within said slot 80 and secured thereby, means to attach said chain to the upper of said sections and a spring surrounding said chain within said tube and adapted to pull said chain into said tube when said chain is released from said 85 last-mentioned section and the link thereof removed from said slot.

In testimony whereof I have hereunto set my hand in presence of two subscribing witnesses.
